REVERSIBLE ACTION AUTOMATIC LOCK SLIDER

Louis H. Morin, Bronx, N.Y.
(125 Beechwood Ave., New Rochelle, N.Y.)

Filed May 15, 1958, Ser. No. 735,495

3 Claims. (Cl. 24—205.14)

This invention relates to what I term reversible action automatic lock sliders adapted for use upon reversible garments so as to at all times expose a pull at the outer surface of the garment for coupling and uncoupling separable fastener stringers. More particularly, the invention deals with a slider of the character described wherein a yoke enveloping the slider walls is pivotally mounted upon one wall of the slider and tensional means is employed for normally supporting the locking lugs of the yoke in operative position.

Still more particularly, the invention deals with a slider structure of the character described wherein each pull disposed on opposed walls of the slider can operatively engage the yoke in movement of the locking lugs into inoperative position against the action of said spring for movement of the slider along the stringers.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a face view of one side of a slider made according to my invention, with part of the construction shown in section and with part broken away.

Fig. 2 is a view similar to Fig. 1 illustrating the reverse side of the slider with part of the construction broken away.

Fig. 3 is an enlarged sectional view on the broken line 3—3 of Fig. 1, with parts of the construction shown in elevation; and

Fig. 4 is a section on the line 4—4 of Fig. 3, omitting all background showing.

Considering Fig. 3 of the drawing, I have shown at 10 a slider having a pair of walls 11 and 12 joined and spaced by connecting web 13 at the wide end portion 14 of the slider body, these wide end portions being illustrated in Figs. 1 and 2 of the drawing.

At 15 and 16 respectively are shown the inwardly extending flanges at adjacent surfaces of the walls 11 and 12 for guidance of the scoops of separable fastener stringers into the channel of the slider body, as with other devices of this type and kind.

At 17 in Fig. 3 of the drawing, I have indicated in dotted lines diagrammatically the position of a scoop within the channel of the slider, particularly indicating its engagement with the locking lugs of the slider later described.

The wall 11 of the slider has at the wide end portion thereof a projecting lug 18 having a transverse aperture 19 therein, as clearly noted in Fig. 1 of the drawing. This wall of the slider, including the web 13, has a deep aperture 20 for the reception of and mounting of a coil spring 21. The narrow end portion of the wall 11 has an outwardly projecting stop bridge 22 and the wall 11 has an elongated aperture 23 which extends beneath the bridge 22, as clearly noted in Fig. 3.

2

The wall 12 of the slider has centrally of the end of the wide end portion 14 of the slider a projecting abutment 24. The wall 12 at the narrow end portion has a projection 25 for the purpose of balancing the appearance of the slider at both walls thereof, the projection terminating adjacent the wide end 14 of the slider in a slot 26, note Fig. 2 of the drawing, this slot being adapted to receive and guide a projecting tongue 27 at one end of a locking yoke 28. The end of the yoke 28 having the projection 27, includes an inwardly projecting shoulder 29 in conjunction with which the rounded pin end 30 of one pull 31 is adapted to operate as later described.

The other end portion of the yoke 28 includes a pair 15 of offset locking lugs 32 which are adapted to operate in conjunction with the fastener scoops in retaining the slider in locked position upon the stringers of a separable fastener. This end portion of the yoke 28 includes a projecting finger 33 adapted to operate in conjunction with 20 the projecting bridge 22 in checking outward swinging movement of the yoke in operation of the pull 31 or the pull 34 arranged upon the wall 11.

It will appear from a consideration of Fig. 3 of the drawing that the innermost locking lug 32 has a long 25 beveled surface 35 in conjunction with which the pin end 36 of the pull 34 operates in swinging the yoke outwardly in movement of the lugs 32 into inoperative position with respect to the scoops. This same result is accomplished by engagement of the pin end 30 of the pull 31 with the inwardly projecting shoulder 29.

It will appear from a consideration of Fig. 3 of the drawing that the end portions of the yoke 28, including the lug 32, are free to move in the aperture 23 of the wall 11.

35 The second named end portion of the yoke 28 has substantially centrally thereof an aperture 37 for free reception of the lug 18 and opposed walls 38, bordering the aperture 37, includes inwardly projecting pivot pins 39, note Fig. 1 of the drawing, which operate in the aperture 19 of the lug 18.

The yoke is preferably a die cast part and in the casting operation the walls 38 are spread sufficiently to clear the pivot pins 39 over the lug 18, after which pressure is applied to the side walls 38 to move the pins 39 into 45 operative engagement with the lug 18, the result of this operation being shown on the finished product as illustrated in Fig. 1 of the drawing.

It will appear from a consideration of Fig. 3 of the drawing that the side walls 38 include inward extensions, 50 one of which is shown at 38' in Fig. 3 of the drawing, to provide ample bearing surface upon the lug 18 and also to partially house the spring 21.

The projections 38' form a recess 40 in the yoke adjacent the aperture 37, and the base of the recess includes a projection 41 upon which the outer end portion of the spring 21 is seated, as clearly noted in Fig. 3 of the drawing.

While the cross head portion 42 of the yoke could 60 integrally join the end portions of the yoke, in the structure as shown the yoke is made of a long part 43 and a short part 44, and considering Fig. 4 of the drawing it will appear that these parts have reduced overlapping portions 45 and 46 respectively, each having a projecting tapered rivet pin 47 and 48 respectively, the pin 47 being insertable into an aperture 49 in the portion 46, whereas the pin 48 seats in a corresponding aperture 50 in the portion 45. When the pins 47 and 48 are riveted over, as diagrammatically noted in Fig. 4 70 of the drawing, the crosshead 42 of the yoke is made as one.

It will appear from a consideration of Fig. 3 of the

drawing that in movement of the slider in the direction of the arrow 51 by either of the pulls 31 and 34, the lugs 32 will be moved into inoperative position, permitting free movement of the slider along the fastener stringers. On the other hand, in movement of the slider in the direction of the arrow 52 by either of the pulls 31, 34, the pull 31 or the pin end 30 thereof will strike the abutment 24, whereas the pin end 36 of the pull 34 will strike the lug 18, and the yoke will ratchet over the fastener scoops, which ratcheting is against the action of the spring 21 as will be apparent.

It will appear from a consideration of Fig. 2 that the pull 31 has a large aperture 53 to clear the projection 25 when the pull is in collapsed position, and the pull 34 has an aperture 54 to clear the bridge 22 when the pull is in collapsed position, the apertures 54 and 53 being clearly shown in Figs. 1 and 2.

By way of summary, and for descriptive purposes the long part 43 of yoke 28 may be termed a lock element or lock element portion, and this is pivotally attached to one wall of the slider and has locking projections 32. The short part 44 of yoke 28, which is disposed on the opposite wall, may be termed a member, and this is joined to the lock element by means, disposed outwardly of the web, comprising the crosshead portion 42, there being thereby formed the yoke or yoke-like piece 28. A second member 25 is immovably fixed to the said opposite wall. The first member 44 movably engages the second member through the interengaging means 26, 27, the interengaged members thus simulating the lock element portion 43. As noted, each pull when drawn in the fastener-opening direction engages and moves the said yoke-like piece about the pivot of the lock element portion thereof, thereby to move the locking projections out of the channel and to unlock the slider. When either pull is drawn in the fastener-closing direction, it engages a fixed portion of the slider, projection 18 or abutment 24, so that the yoke-like piece is not moved about the said pivot and so that the locking projections ratchet over the fastener.

Having fully described my invention, what I claim as new and desire to secure by Letters Patent is:

1. A lock slider for separable fastener stringers comprising a channelled slider body defined by walls joined and spaced by a connecting web at a wide end of the slider body, a lock yoke enveloping the slider body, said yoke having a long part arranged upon one wall of the slider and a short part upon the other wall, said parts being joined in a crosshead extending over the wide end of the slider body, means on said first named wall and the long part of said yoke for pivoting the yoke on the slider body, the free end of the long part of the yoke having locking lugs adapted to extend into the channel of the slider body at a narrow end portion of said body, tensional means operating upon the long part of said yoke for normally supporting said locking lugs in operative position in the channel of the slider body, a pair of pulls, one pull being arranged and operating upon the first named wall of the slider body and adapted to simultaneously engage the long part of said yoke and said first mentioned wall for movement of said locking lugs into inoperative position against the action of said tensional means, the other pull being arranged upon the other wall of the slider body between said yoke and said other wall and operatively engaging the short part of said yoke in moving said locking lugs into inoperative position against the action of said tensional means, and means on the second named wall adjacent the wide end of said slider and under said short end of said yoke for checking movement of the second named pull in one direction of said wall.

2. A lock slider for separable fastener stringers com-

prising a channelled slider body defined by walls joined and spaced by a connecting web at a wide end of the slider body, a lock yoke enveloping the slider body, said yoke having a long part arranged upon one wall of the slider and a short part upon the other wall, said parts being joined in a crosshead extending over the wide end of the slider body, means on said first named wall and the long part of said yoke for pivoting the yoke on the slider body, the free end of the long part of the yoke having locking lugs adapted to extend into the channel of the slider body at a narrow end portion of said body, tensional means operating upon the long part of said yoke for normally supporting said locking lugs in operative position in the channel of the slider body, a pair of pulls, one pull being arranged and operating upon the first named wall of the slider body and adapted to simultaneously engage the long part of said yoke and said first mentioned wall for movement of said locking lugs into inoperative position against the action of said tensional means, the other pull being arranged upon the other wall of the slider body between said yoke and said other wall and operatively engaging the short part of said yoke in moving said locking lugs into inoperative position against the action of said tensional means, and said second named wall having a projecting part forming an extension to the short part of said yoke, and said projection and short part of the yoke having interfitting portions for definitely positioning the short part of the yoke on said second named wall.

3. A lock slider for separable fastener stringers comprising a channelled slider body defined by walls joined and spaced by a connecting web at a wide end of the slider body, a lock yoke enveloping the slider body, said yoke having a long part arranged upon one wall of the slider and a short part upon the other wall, said parts being joined in a crosshead extending over the wide end of the slider body, means on said first named wall and the long part of said yoke for pivoting the yoke on the slider body, the free end of the long part of the yoke having locking lugs adapted to extend into the channel of the slider body at a narrow end portion of said body, tensional means operating upon the long part of said yoke for normally supporting said locking lugs in operative position in the channel of the slider body, a pair of pulls, one pull being arranged and operating upon the first named wall of the slider body and adapted to simultaneously engage the long part of said yoke and said first mentioned wall for movement of said locking lugs into inoperative position against the action of said tensional means, the other pull being arranged upon the other wall of the slider body between said yoke and said other wall and operatively engaging the short part of said yoke in moving said locking lugs into inoperative position against the action of said tensional means, and the long and short parts of the yoke including at the crosshead portion overlapping parts and means securing said parts together.
